UNITED STATES PATENT OFFICE

2,655,336

COMBINATION CURTAIN, SHADE, AND DRAPERY BRACKET

Dorothy M. McGowan, Parkland, Wash., assignor
of fifty per cent to John R. McGowan, Park-
land, Wash.

Application July 19, 1950, Serial No. 174,755

2 Claims. (Cl. 248—259)

1

The present invention relates to new and useful improvements in combined curtain, shade and drapery brackets and more particularly to a fixture of this character wherein a single mounting is constructed with all of the fittings necessary to support curtain and drapery rods and a shade roller.

An important object of the invention is to provide an attaching plate having means for slidably supporting a horizontally adjustable drapery rod of novel construction to provide a desired overlap with respect to a curtain also supported on the attaching plate.

Another object is to provide a fixture of this character of simple and practical construction, which is strong and durable, neat and attractive in appearance, relatively inexpensive to manufacture and otherwise well adapted for the purposes for which the same is intended.

Other objects and advantages reside in the details of construction and operation as more fully hereinafter described and claimed, reference being had to the accompanying drawings forming part hereof, wherein like numerals refer to like parts throughout, and in which:

Figure 1 is a perspective view;

Figure 2 is a horizontal sectional view taken on a line 2—2 of Figure 1; and

Figure 3 is a vertical sectional view taken on a line 3—3 of Figure 1.

Referring now to the drawing in detail, wherein, for the purpose of illustration, I have disclosed a preferred embodiment of my invention, the numeral 5 designates an attaching plate constructed with a front plate 6 and a rearwardly extending plate 7 formed angularly to each other and with the plate 7 attached to the inner edge of a window frame 8 by screws 9 to position plate 6 against the front surface of the frame.

The end section of an extensible drapery rod is shown at 10 and comprises a rear bar 11 having a forwardly projecting end portion 12 at right angles to the outer end of the rear bar and a front bar 13 extending inwardly from the front end of end portion 12 and united therewith by a rounded corner 14 to support front bar 13 parallel to and spaced in front of rear bar 11.

Rear bar 11 is formed with a longitudinal slot 15 slidable on a bolt and wing nut 16 and a pair of supporting pins 17 carried by front plate 6 to support the display rod in horizontally adjusted position on the window frame.

A curtain rod supporting hook 18 is suitably secured to front plate 6 in a forwardly projecting position under the display rod and with the up-

turned end 19 of the hook positioned between the front and rear bars of the drapery rod.

A shade roller supporting bracket 20 is also secured to the front plate 6 below hook 18 and inwardly with respect thereto.

The drapery rod 10 may be adjusted inwardly or outwardly on bolt and wing nut 16 and supporting pins 17 to provide a desired overlap at the side of the window with respect to a curtain rod supported on hook 18 and which supports a curtain 21 behind a drapery 22 supported on front bar 13 of the drapery rod 10. The shade roller bracket 20 supports a shade roller 23 behind and inwardly of the ends of the curtain 21 and also behind the drapery 22.

In view of the foregoing description taken in conjunction with the accompanying drawings, it is believed that a clear understanding of the device will be quite apparent to those skilled in this art. A more detailed description is accordingly deemed unnecessary.

It is to be understood, however, that even though there is herein shown and described a preferred embodiment of the invention, the same is susceptible to certain changes fully comprehended by the spirit of the invention as herein described and within the scope of the appended claims.

Having described the invention, what is claimed as new is:

1. A combined curtain, shade and drapery attachment for windows comprising an angle bracket including first and second flanges, said first flange having apertures therethrough for the reception of fasteners to attach the same to a window frame, and vertically spaced drapery, curtain and shade supporting means mounted on said second flange, said drapery supporting means comprising a pair of horizontally spaced guide pins projecting from said second flange and a threaded stud between said pins, a U-shaped rod comprising first and second legs and a web interconnecting said legs, said first leg having a longitudinal slot therein slidably mounting said first leg on said guide pins, said second leg being adapted to receive a drapery and a headed fastener on said threaded stud to clamp the first leg in a selected position.

2. A combined curtain, shade and drapery attachment for windows comprising an angle bracket including first and second flanges, said first flange having apertures therethrough for the reception of fasteners to attach the same to a window frame, and vertically spaced drapery, curtain and shade supporting means mounted on

said second flange, said drapery supporting means comprising a pair of horizontally spaced guide pins projecting from said second flange and a threaded stud between said pins, a U-shaped rod comprising first and second legs and a web interconnecting said legs, said first leg having a longitudinal slot therein slidably mounting said first leg on said guide pins, said second leg being adapted to receive a drapery and a headed fastener on said threaded stud to clamp the first leg 10 in a selected position, said curtain supporting means comprising a hook disposed below said guide pins and said blind supporting means comprising a lug projecting from said second flange below said hook and having a notch for receiving 15 a shade roller.

DOROTHY M. McGOWAN.
